UNITED STATES PATENT OFFICE.

RANDOLPH F. HALL, OF ITHACA, NEW YORK, ASSIGNOR OF ONE-FOURTH TO THEODORE P. HALL, OF WALLINGFORD, CONNECTICUT, AND ONE-FOURTH TO PAUL WILSON, OF ITHACA, NEW YORK.

AIRPLANE.

Application filed December 31, 1924. Serial No. 759,081.

To all whom it may concern:

Be it known that I, RANDOLPH F. HALL, a citizen of the United States of America, and a resident of Ithaca, county of Tompkins, State of New York, have invented certain new and useful Improvements in Airplanes, of which the following is a specification.

This invention relates to certain improvements in airplanes, and the nature and objects of the invention will be readily recognized and understood by those skilled in the arts involved in the light of the following explanation and detailed description 15 of the accompanying drawings illustrating what I at present consider to be the preferred embodiments or mechanical and aerodynamical expressions of the invention from among various other forms, arrangements, 20 combinations and constructions of which the invention is capable within the spirit and scope thereof.

In the arming of aircraft for offensive and defensive purposes it is an aim and desire to so mount such ordnance on the craft as to obtain therefrom as wide and as unrestricted a range of fire in all directions from the craft as is possible, in order to secure a maximum protection or offensive 25 strength from the ordnance with a minimum of vulnerability in the defense of the craft. However, due to the design, construction and aerodynamical characteristics of aircraft, and particularly such craft of the 30 heavier-than-air or airplane types, certain problems are encountered and disadvantages result in practically carrying out the above aim in the attempt to secure the desired wide and unrestricted range of fire 35 from aircraft mounted ordnance and the resulting offensive and defensive efficiency of such ordnance.

The conventional and prevailing manner of arming aircraft in general use and familiar in this art, embodies the mounting of the ordnance in the form of machine guns, cannon or the like, hereinafter referred to in a broad generic sense as guns, at fixed locations on the craft by mounts 40 which permit of adjustment of the guns in both a horizontal and a vertical plane. These mounts are generally located on an element of the aircraft, such as the fuselage, nacelle or wing thereof adjacent a

cockpit or gunner's station from which they 55 are accessible for operation by a gunner, and are limited to the extent of exposed structure due to the prime necessity in aircraft for maintaining head or parasite resistance at a minimum, as well as to maintain the mount within operating reach of the gunner, so that the range of adjustment of a gun so mounted is accordingly limited. With the foregoing mounting of a gun at a fixed location the range of fire thereof 60 is materially restricted by intervening structure of the aircraft with the result that "blind angles" are created through which it is not possible to fire the gun, and the offensive and defensive efficiency thereof is 65 lowered and the vulnerability of the craft to attack is increased. The correction of these so-called "blind angles" of an aircraft mounted gun by the mounting of additional guns on the craft at locations to permit of 70 their firing through such "blind angles" 75 entails an increase in weight of the craft and the lowering of the general efficiency and performance thereof, while the elimination or reduction of these angles through structural and design changes in the craft is not generally possible or feasible for aerodynamical and strength reasons, as will be readily understood by those familiar with 80 the aeronautical art.

Hence, one of the fundamental aims and objects of the present invention is to increase the effective range of fire of ordnance mounted on aircraft, with a resulting reduction in "blind angles" and increase in the 85 offensive and defensive efficiency of aircraft mounted and carried ordnance, without material increase in the parasite resistance or weight of the craft, or reduction in the general aerodynamic performance thereof.

A further object of the invention is the provision of an ordnance or gun mount for aircraft which is capable of movement to various positions on and with respect to the element of the craft on which mounted 100 so as to increase the effective range of fire of a gun carried by the mount, and which is so designed as to be readily accessible to a gunner for operation of the gun in the various positions of the mount on the element, without material decrease in the aerodynamical efficiency or performance of the craft on which mounted.

A further object of the invention is to provide an ordnance mount for aircraft which is movable to various locations on the craft to increase and vary the range of fire thereof, and in which provision is made for automatically operating control surfaces of the craft to compensate for the shift of the weight of the mount to different points and thus maintain the proper balance and equilibrium of the craft in operation.

A further object of the invention is the provision of an ordnance or gun mount for aircraft which is movable to different positions on the element of the craft on which mounted, and which embodies a novel gunner's seat movable with the mount to the various positions on the aircraft element.

A further object of the invention is to provide an ordnance or gun mount for aircraft which is movable along and over an elongated open cockpit or passageway for a gunner formed in the element of the aircraft on which the mount is movably mounted, with a cover or closure for the passageway automatically operated by the mount to maintain the passageway closed in all positions of the mount and thus prevent material interruption in the surface or contour of the element and resulting loss in aerodynamic efficiency.

A further object of the invention is to provide an ordnance or gun mount for aircraft, movable to various positions on the craft and carrying a gunner's seat from which the ordnance on the mount is operable, and which mount is movable to the various positions on the aircraft by the gunner.

A further object of the invention resides in the design, construction and arrangement of an elongated or extended open gunner's cockpit or passageway in an aircraft element without materially decreasing the factor of safety of the element or the aerodynamical efficiency thereof, and from which passageway ordnance mounted on the element can be operated.

Another object of the invention is to increase the useful load or weight carrying capacity of armed aircraft, by providing gun mounts which will permit of a reduction in the total number of guns necessary to effectively provide the desired offensive and defensive strength of the craft.

Another object of the invention is to provide ordnance or gun mounts for aircraft which will permit of a concentration of the ordnance or guns carried thereby at the most effective points on the craft to meet the exigencies and conditions developed during combat with the aircraft on which mounted.

A further object of the invention is to provide an ordnance mount for aircraft which is capable of and adapted for mounting on an aircraft at any desired point on a major element thereof, such as the body,

sustaining surfaces or the like, for movement to various positions on and with respect to the element on which mounted and installed.

Still further objects of the invention are to provide certain improvements in the details of design, construction and mounting of movable aircraft ordnance or gun mounts to increase the efficiency of such mounts in operation and use on aircraft.

With the foregoing general objects and certain other objects and results in view, which other objects and results will be readily apparent from the following explanation, the invention consists in certain novel features in construction and in combination and arrangement of elements, as will be more fully and particularly referred to and specified hereinafter.

Referring to the accompanying drawings: Fig. 1, is a view in side elevation, partly in section, of a portion of an airplane fuselage with the ordnance mount and gunner's seat of the invention mounted in operative position thereon, and showing more or less diagrammatically the gun mount actuating mechanism for operating a control surface of the airplane, the skin of the fuselage being partly removed.

Fig. 2, is a view in top plan of a portion of the fuselage of an airplane with the skin or covering removed, formed to provide the elongated open top gunner's cockpit, and showing the gun mount and seat of the invention mounted thereon.

Fig. 3, is a top plan view more or less diagrammatical, of an airplane provided with a gun mount of the invention on the fuselage thereof, and further showing a mount of the invention mounted on a wing of the airplane and disclosing the mount actuated mechanism for operating lateral control surfaces on the wing.

Fig. 4, is a view in front elevation of the airplane of Fig. 3, showing the wing ordnance mount thereon.

Fig. 5, is a diagrammatical view in side elevation of a gunner's nacelle mounted on a thin section type wing and having an ordnance mount of the invention mounted thereon.

Fig. 6, is a front elevation of the nacelle and mount of Fig. 5, a portion only of the wing being shown.

Fig. 7, is a diagrammatical sectional view through a thick section type of wing formed with a gunner's cockpit therein and showing the ordnance mount actuated cover therefor.

Fig. 8, is a transverse, vertical sectional view through the fuselage of Fig. 2 showing the construction and arrangement thereof to form the gunner's cockpit and the gun mount receiving track with the mount and seat in operative position therein and thereon.

Fig. 9, is a longitudinal, vertical sectional

view through a portion of the fuselage of Fig. 2, showing the gun mount and gunner's seat in side elevation with the folded position of the seat indicated in dotted outline.

5 Fig. 10, is a detail sectional view through the gun mount of the invention showing a form of operating mechanism for moving the mount.

10 Fig. 11, is a detail section through the mount and form of operating mechanism of Fig. 10.

15 Fig. 12, is a view in top plan showing the gun mount of the invention mounted on the airplane fuselage with the mount operated cover or closure for the gunner's cockpit or passageway formed in the fuselage.

20 Fig. 13, is a diagrammatical view in edge or side elevation of the gun mount with the cockpit closure or cover and winding rolls for the cover.

Fig. 14, is a detail sectional view showing the cockpit cover and one of the edge guides therefor.

25 Fig. 15 is a detail sectional view through a portion of the cockpit cover or closure showing one of the strengthening or stiffening stays therefor.

30 Fig. 16, is a more or less diagrammatical view in top plan of an airplane of the multiplane type provided with opposite side gunner's nacelles between the wings thereof and having ordnance mounts of the invention mounted thereon.

35 The invention is disclosed in the accompanying drawings and described herewith as mounted on and applied to aircraft of the heavier-than-air or airplane types, but this disclosure is purely for purposes of example and not by way of limitation, as the invention and the several features thereof are of general application to aircraft of both the lighter-than-air and the heavier-than-air types, while certain features thereof are of general application for the mounting of ordnance, as will be recognized by those skilled in the art. The embodiments of the invention shown herewith for application to aircraft of the airplane types, are presented because the several problems solved and disadvantages overcome are encountered in a high degree in airplanes, and hence these embodiments and their application serve to more clearly bring forth and exemplify the principles and various features of the invention.

40 According to the invention an ordnance or gun mount is installed and mounted on an element of an airplane for movement thereon to various positions, in such a manner that the gun carried by the mount is operable in all positions on the element by a gunner. One embodiment of the invention is disclosed in the accompanying drawings as applied to and installed on the body or 45 fuselage of an airplane for movement in

a longitudinal or fore and aft direction to various positions thereon, the fuselage being formed to provide an extended cockpit or passageway through which a gunner moves with the gun mount to the various 70 positions on the fuselage. In this embodiment and application of the invention, referring now to Figs. 1, 3 and 16 in particular, the fuselage or body 10 of an airplane of conventional or other design or type 75 embodying the usual supporting surfaces 11, of the monoplane or multi-plane types, and the empennage or tail unit 12, is formed with an elongated or extended passageway 80 or cockpit 14 disposed longitudinally of the fuselage 10 between empennage 12 and the supporting surfaces 11, which cockpit opens through the upper side of the fuselage. An ordnance or gun mount M is 85 movably mounted on the fuselage 10 over the passageway or cockpit 14 for movement therealong to various positions on the fuselage, and in the present example, although not so limited, embodies an annular structure 90 extending across the cockpit 14 and within and by which the gunner stands and is surrounded to operate a gun mounted and carried thereon, in the usual manner.

95 A possible design and arrangement of the fuselage 10 to provide the gunner's passageway or cockpit 14 therein, which will be unobstructed from end to end thereof and open along and through the top or upper side of the fuselage, while retaining in the fuselage the requisite strength and aerodynamic characteristics, is illustrated in detail by Figs. 1, 2, 8 and 9 of the accompanying drawings. In this instance and as an example, the fuselage 10 is of the trussed metal frame type and embodies the upper and lower tubular longérons or longitudinals 15 and 16, respectively, connected and joined at the opposite sides of the fuselage, respectively, by the spaced vertical struts or compression members 17, with any suitable or desired arrangement of diagonal brace wires 17' (see Fig. 9) arranged between the upper and lower longérons 15 and 16, and members 17 at each side of the fuselage. The lower longérons 16 are connected and joined by the series of horizontal, spaced cross members or struts 18, and suitable fairing 19 is provided depending from and forming the lower or under side of the fuselage, all in the more or less conventional 100 manner familiar in this art. However, instead of the conventional construction of the fuselage and frame at the upper side thereof with the usual series of spaced horizontal cross members or struts, such as the cross member 20 at the rear or tail end of the fuselage between upper longérons 15 (see Fig. 2), the invention provides a 105 trussed frame arrangement and construction by which the unobstructed, open top 110

passageway or cockpit is formed and the required directional and torsional stiffness and strength of the fuselage frame is maintained without weakening the fuselage or detracting from the aerodynamic efficiency thereof.

At the upper or top side of the fuselage 10 a pair of spaced, substantially parallel rods or tubes 21 are disposed longitudinally of the fuselage between and spaced inwardly a distance from the upper longérons 15, respectively. These rods 21 substantially define the length and width of the upper open side of the passageway 10, and in the present example extend from a point forward of the empennage 12 on the fuselage (cross member 20) to a point aft or to the rear of the supporting surfaces 10. Each rod 21 is secured to and connected with the adjacent frame longeron 15 by a series of spaced horizontally disposed members or bars 22 extending between rod 21 and longeron 15, above and in substantially the same vertical plane as the cross members or struts 18, respectively, between the lower longérons 18. Vertically disposed diagonal brace members or struts 23 extend downwardly and inwardly from the point of connection or juncture of each member 22 with the adjacent longeron 15, to the substantial centers of the members 18 therebelow, respectively, so that spaced pairs of these brace members 23 are formed converging downwardly from the upper longérons 15 to the center of the respective member 18 therebelow, and form, with rods 21 and members 22, trusses supporting rods 21 and the upper side of the fuselage.

A series of spaced cross bars 24 are extended between and secured to the pairs of opposite vertical struts 17, respectively, spaced above and in substantially the same vertical plane as the cross members 18, respectively, opposite horizontally disposed longitudinal bars 25 being preferably interposed between the ends of cross bars 24 and the adjacent vertical struts 17, respectively, as particularly shown in Figs. 8 and 9. The cross bars 24 are intersected and joined by the vertical converged struts 23 and thus form therewith, in effect a central, triangular truss beneath the bars 18 and connecting the same with and supporting such bars from the cross members or struts 18 between the lower longérons. Additional truss members 26 are secured extending downwardly and outwardly from the point of connection of each strut 23 with a cross bar 24, to the point of connection of the adjacent cross member 18 with a longeron 16, thus forming a vertically disposed truss extending across the fuselage between the lower end portions of the pairs of vertical struts or compression members 17, respectively. Any suitable or desired flooring 27 is mounted

and supported on the cross bars 24 and longitudinal bars 25 to form a support for a gunner throughout the length or extent of the cockpit or passageway 14.

The fuselage frame formed and constructed as above described is covered or enclosed by any suitable or desired material 28 (see Fig. 1) in the usual manner to form and complete the fuselage 10, this covering extending upwardly from the fuselage sides over and across the space between the rods 21 and the upper longérons 15 and terminating at and along rods 21 so as to leave the upper side of the cockpit or passageway 14 open and unobstructed. By the foregoing construction of the fuselage 10 and frame therefor, the elongated or extended longitudinally disposed cockpit 14 is formed, open at its upper side and unobstructed throughout its extent without structurally weakening the fuselage or decreasing the aerodynamic efficiency thereof through interruptions or deformations in the contour or shape thereof. The principles in design and construction exemplified by the fuselage 10 are not limited to such element of an aircraft, as a cockpit or passageway of the character disclosed can be formed in any aircraft element having the general characteristics of an enclosed and trussed frame, such for example as the wing or supporting surface of an airplane, and the invention contemplates and includes such formation or its equivalent in any suitable element.

The ordnance or gun mount M for installation on the fuselage 10 for operation by a gunner from the cockpit or passageway 14, in the example hereof embodies a lower or base ring 30 and an upper ring 31 rotatably mounted and superposed thereon, as clearly shown by Figs. 8, 9, 10 and 11 of the drawings in particular. The upper ring 31 is rotatably mounted on the lower ring 30 in any well known or suitable manner, as by the interposition of anti-friction rollers, balls or the like (not shown) between the rings in the usual manner. The rings 30 and 31 are horizontally disposed on the upper side of fuselage 10 across cockpit 14 for movement longitudinally therealong, with the upper ring rotatable on the lower or base ring 30. Grooved rollers 32 are rotatably mounted and journaled on suitable pins or stub shafts depending from and carried by the lower or base ring 30, and are so disposed and located thereon with respect to the opposite side parallel rods 21 of fuselage 10 and cockpit 14, as to fit onto and receive said rods which form a supporting and guiding track therefor and maintain the rings in mounted position on the fuselage. Thus, the rings 30-31 are movably or slidably mounted and confined on the rods 21 for movement thereon along and longitudinally of the cockpit 14

and fuselage 10 to any desired position along the said cockpit, the lower or base ring 30 being fixed against rotation or lateral movements by the supporting rollers 32, while the upper ring 31 is freely rotatably mounted and confined on the base ring.

In order to provide for locking or confining the rings 30-31 of the mount 17 in the desired position on the rods 21 and over the cockpit 14, a manually operable, spring controlled lock lever 33 is pivotally mounted on the under side of base ring 30 adjacent one of the cockpit side rails 21 for engagement with any desired one of a series of bores or recesses 34 formed at spaced intervals along the inner side of such rod 21. The spring 35 of the lever (see Fig. 2) normally forces the same into engaging position, so that to release the lever and permit movement of rings 30-31 along rails 21, the lever is manually swung against the tension of spring 35 away from rail 21 to non-engaging position, as will be clear by reference to the accompanying drawings.

Any suitable or desired ordnance, such as the machine gun G shown in Fig. 1, is mounted and supported on the upper ring 31 for rotation therewith by means of the usual adjustable mechanism G' well known and in general use for this purpose to permit of vertical adjustment or raising or lowering of the gun G, the gun being adjustable in a horizontal plane by rotation with the ring 31 on the base ring 30, as will be readily understood by those familiar with this type of ordnance mounting. In operation and use of the movable mount M with gun G carried thereby, a gunner is stationed in the cockpit 14 and stands in position surrounded by rings 30 and 31 with the gun G accessible for firing operations. When the gunner desires to change the angle of fire of gun G to avoid, for example intervening structure of the airplane with respect to the objective, lever 33 is released and the gunner moves to the desired point in cockpit 14, sliding the gun mount M supported on rods 21 by rollers 32, to the desired location and then releasing lever 33 to engage one of the recesses 34 and lock the mount in the new position on the fuselage 10. In Fig. 1 of the drawings the forward position of mount M is shown in full lines with possible lines of fire F, with respect to the wings 11 and empennage 12 shown by broken lines, while a rearward or aft position of mount M is diagrammatically indicated by dotted lines with possible lines of fire F' shown by broken lines. The mount M is of course movable to any desired point between the disclosed positions by the gunner, and it follows that with the mount so movable longitudinally along fuselage 10 and cockpit 14 the range of fire of gun G is materially increased while the "blind angles" are

substantially decreased with increased offensive and defensive efficiency from gun G or other ordnance carried by mount M.

The shifting or changing of the weight of the mount M and the weight of the gunner, to the different positions along the cockpit 14 longitudinally of the fuselage 10 in operation of the mount, will tend to upset or disturb the proper balance or equilibrium of the airplane on which mounted by this redistribution and changing of the weights along the fore and aft axis of the craft, and the invention provides for effectively compensating for these conditions to maintain the proper longitudinal equilibrium of the airplane. The empennage 12 includes the usual or any desired horizontal stabilizer surface 36, referring now to Figs. 1 and 2 of the drawings, and this stabilizer is pivotally mounted adjacent its leading edge by a pivotal mounting 37 to permit of vertical adjustment or raising and lowering of this stabilizer surface. The mount M is suitably operatively connected with stabilizer 36 so as to raise and lower the same to properly compensate for the shifting of weight in moving the mount along the fuselage. In the present embodiment of this feature, the lower or base ring 30 of mount M is provided with a lug or eye member 38 to which the ends of a cable or line 39 are connected. The cable 39 extends over and between pulleys or rollers 40 mounted at the forward and after ends, respectively, of the cockpit 14 in the upper portion thereof, and operatively over suitable reduction mechanism or gearing 41 (see Fig. 1) mounted forwardly of and below the after pulley 40, as will be clear by reference to Fig 1 of the drawings. An adjustment rod 42 depends within the tail of fuselage 10 from the stabilizer 36 and is pivotally coupled to the horizontal arm of a pivotally mounted bell crank lever 43. A cable 44 is operatively connected at its ends to the ends, respectively of the vertical lever of bell crank 43, and extends rearwardly around and over a take-off pulley 45 operated by the reduction gearing 41. With the foregoing mechanism, movement of the mount M in either a forward or rearward direction along fuselage 10 will cause cable 39 to rotate the reduction gearing 41, which in turn will operate the pulley 44 to swing bell crank 43 through cable 44, and results in elevating or lowering the stabilizer 36 in accordance with the direction of movement of mount M, that is, to raise the stabilizer on forward movement of the mount and lower it on rearward movement of the mount as will be readily understood. The reduction mechanism or gearing 41 is purely diagrammatically disclosed herewith, as any desired or suitable type or arrangement thereof may be utilized to obtain the required movement of pulley

41 and elements operated thereby with respect to the movement of the mount M to properly adjust stabilizer 36. In this manner, the changes in location of the center of gravity of the airplane by shifting the weight of mount M and the gunner along the fuselage are automatically compensated for by stabilizer 36, and the balance of the airplane maintained.

5 With the elongated or extended open top or side cockpit 14 formed in the fuselage 10, the aerodynamic efficiency of the fuselage may be lowered by this open cockpit, and the invention eliminates this condition through the medium of an automatically operated and controlled cover or closure which maintains the cockpit closed and substantially carries out the shape or contour thereof irrespective and in any position, of the mount M thereon. A possible embodiment of this feature of the invention is disclosed in Figs. 12 to 15, inclusive of the accompanying drawings. The gun mount M is provided with a forwardly extending flange 46 and a rearwardly extending flange 47, preferably although not necessarily, formed of sheet metal and secured to the lower or base ring 30 of mount M. A strip or length of fabric or other suitable material 48 is secured at one end to the forward flange 46 of mount M and extends forwardly therefrom over and covering the portion of cockpit 14 forward of the mount, and a similar strip of fabric 49 is secured to rear flange 47 and extends rearwardly therefrom over and covering the portion of the cockpit aft of mount M. These strips of material 48-49 extend over and close the cockpit 14 from end to end thereof, with the exception of that part over which mount M extends and through which the cockpit is open and accessible, and form and provide the cockpit cover or closure 50.

45 At each end of cockpit or passageway 14, a roller 51 is mounted within the fuselage and disposed horizontally and transversely thereof. The rollers 51 are preferably of the well known and understood spring-actuated self-winding "curtain roller" type, although any other suitable type of roller or winding mechanism may be employed. The free ends of the strips 48 and 49 of cover 50 are attached to and wound on these rollers 51, so that the strips are maintained taut and without slack, stretched between the mount M and the rollers, and covering and closing the cockpit 14. Suitable opposite edge guide members or flanges 52 (see Fig. 14) are provided for the cover 50 and in the present example are secured to the members 21 and 22 of the fuselage frame and extend over and confine the edge portions of the cover 50 against displacement, the cover freely sliding under and along these guides 52, as will be clear from Figs.

12 and 14 of the drawings. Preferably, where the cover 50 is formed of fabric material suitable transverse stays 53 are secured at spaced intervals along the lower or under side of the cover in order to stiffen and strengthen the same while permitting the cover to freely wind and unwind from the rollers 51. A possible manner of securing and mounting these stays is disclosed by and will be readily apparent from Fig. 15 of the drawings.

In operation of the cover 50 formed and mounted as above described, as the mount M is moved along and over cockpit 14, the ends of the strips 46 and 47 of the cover are wound or unwound from the rollers 51, and in all positions of the mount M the cockpit or passageway 14 is covered and closed by this cover, except the portion beneath the mount itself, as will be clear. The cover 50 thus forms in effect, with the fuselage covering at the sides of cockpit 14, the upper covering or skin for that portion of the fuselage occupied by the cockpit 14, and presents the desired substantially unbroken continuous surface carrying out the contour and shape of the fuselage. In this manner the aerodynamic efficiency of the fuselage is maintained, notwithstanding the formation of the elongated or extended cockpit 14 therein, and further the movement of the mount M along this cockpit 14 is possible while maintaining the latter closed.

A further feature of the invention provides a gunner's or occupant's chair or seat movable with mount M and from which the mount and ordnance carried thereby are operable. The construction, arrangement and mounting of this seat or chair is disclosed in Figs. 1, 2, 8 and 9 of the accompanying drawings. A pair of spaced opposite side bars are secured at their upper ends to the rearward or after side of the base ring 30 of the mount M, and depend downwardly therefrom into the cockpit 14 a distance above the floor 27 of cockpit 14. The side bars 60 are converged inwardly and downwardly to and terminate at the floor 27 to form the chair supporting legs or base members 61. Any suitable or desired material is mounted between the side bars 60 above members 61 to form with side members 60, the chair or seat back 62. At the lower ends of side members 60 above and adjacent members 61, a seat or chair bottom 63 is pivotally mounted to and between the forwardly extending ears or lugs 64 (see Fig. 9), and extends horizontally and forwardly from members 60 in normal seat forming position. A support is provided for and between the forward portion of the seat 63 and the lower converged portion of the members 61 to support the seat in normal position, and in the present ex-

ample embodies the telescopic members 65 and 66 (see Figs. 8 and 9). The member 65 is formed by a tube 65 pivotally coupled to the under forward portion of seat 63, and 5 the member 66 is formed by a rod pivotally coupled to the converged members 61 and slidably or telescopically received in the tube 65. If desired, any suitable resilient or spring means (not shown) is mounted in 10 tube 65 upon which the rod 66 bears to form a resilient or spring mounting permitting movement of the seat in normal position to absorb shocks and jars and add to the comfort of an occupant seated 15 thereon. With the foregoing seat construction and mounting, the seat or chair bottom 63 can be folded or swung upwardly and rearwardly on the pivots of ears 64 to a substantial vertical position against the seat 20 back 62 and side bars 60, as shown in dotted outline in Fig. 9, the telescopic support forming members 65 and 66 being extended as shown. In folded position the seat bottom 63 is removed from position obstructing 25 the cockpit space below mount M and the freedom of the gunner or occupant of this space is unhampered thereby.

A track or guideway 67 is provided extending centrally and longitudinally of and 30 along the floor 27 of the cockpit or passageway 14, and in the example hereof embodies a channel member having the side flanges bent over to provide a central opening or slot therealong. The converged end of the 35 members 61 of the seat are extended downwardly through the slot of and into the track or guideway 67 and rollers or wheels 68 are mounted at opposite sides thereof within and bearing on and confined by the guideway 67, as clearly shown by Figs. 8 and 9 40 of the drawings. Floor cleats or the like 69 are secured to the floor 27 of cockpit 14 along opposite sides of the track or guideway 67 for engagement by the feet of a 45 gunner or occupant of the seat 63-62. In use and operation, a gunner in the seat can readily propel or move the same as a unit with the mount M, along the fuselage 10 and through cockpit 14 by engaging the 50 floor cleats 69 and pushing or drawing the seat and mount to the desired position. The mount M during movement thereof 55 slides or rolls along the rails or rods 21, and the seat is guided and the lower end supported by the rollers 68 in the track or guideway 67.

Where relatively heavy ordnance such as a cannon or relatively large caliber gun is mounted on and carried by the mount 60 M, mechanism may be provided for moving or propelling the movement M along the cockpit 14 and fuselage 10. A possible form of such mechanism is illustrated in Figs. 10 and 11 of the accompanying drawings, and embodies a rack, bar or the like

70 secured along the under side of one of the rails or rods 21, with a pinion 71 in mesh or engagement therewith and carried by the lower ring 30 of the mount M. A support or hanger 72 is formed depending 75 from the inner side of the mount base ring 30 adjacent the rack 70 and the pinion 71 is mounted on and fixed to the outer end of a shaft 73 rotatably journaled in and disposed transversely of the hanger 72. A hand operating wheel 74 is mounted and fixed on the inner end of shaft 73 disposed within cockpit 14 and accessible for operation by a gunner in the cockpit. In operation, the hand wheel 74 is rotated by a gunner in the cockpit, or from the seat 63-62, which rotates pinion 71 in engagement with rack bar 70 and propels the mount M along the fuselage 10 and cockpit 14. With such propelling mechanism the 80 mount M is readily moved to the desired position, irrespective of the weight or type of ordnance which may be carried thereby.

The invention contemplates and includes the mounting and installation of the gun mount with the various features of the invention hereinbefore described and explained, on other elements of aircraft than a fuselage or body, such as the fuselage 10, and in Figs. 3, 4 and 7 of the accompanying drawings a possible mounting on the wing of an airplane is disclosed. Referring now to Figs. 3 and 4, an airplane is shown of the monoplane type, although the invention is not limited to monoplanes, having the monoplane wing 11 of the relatively thick or deep section type, including and provided with the usual ailerons 11', or other desired lateral control surfaces. An elongated cockpit or extended passageway 105 14' is formed at the central portion of wing 11, disposed longitudinally thereof and transversely of the fore and aft axis of the airplane. This passageway 14' is similar to that described as formed in the fuselage 110 10, in that it provides an open top and opposite longitudinal rails, rods or the like 21' (see Fig. 7) to receive and on which the ordnance mount M is movably mounted and slidably installed for movement longitudinally of wing 11 and of the passageway 14'. The structure of the wing can be formed in any suitable or desired manner to provide the unobstructed, open top passageway or cockpit 14', without structurally 115 weakening the wing or lowering its efficiency, as for example in accordance with the construction of the fuselage cockpit 14, and further if desired or found expedient can be curved as shown in dotted outline in Fig. 3 to form the arcuate passageway 14''. A gun mount M of the invention, including if desired the hereinbefore described gunner's seat or carried thereby, is mounted 120 on the wing cockpit 14' for movement 125 130

therealong laterally of the airplane to the desired positions, and the cockpit cover or closure 50 is mounted and operatively coupled with mount M to maintain the cockpit or passageway 14' in the wing closed. In order to compensate for the shift in the weight of mount M and the gunner laterally of the airplane, flaps or control surfaces 12' are provided at opposite sides of wing 11 for automatic operation by mount M. Each flap 12' is provided with the usual control mast or horn 75, the opposite ends of which are connected to the ends of a cable 76 extending over and around a pulley 45' carried by suitable reduction gearing or the like 41' mounted within the wing adjacent each flap 12'. The reduction gearing 41' adjacent each control flap 12', respectively are operatively connected and coupled by a cable 77 extending therearound and therebetween. One side or ply of cable 77 is connected with the movable gun mount M, so that, as the mount is moved to one side or the other of wing 11, flaps 12' will be operated to compensate for the shift in weight and maintain the desired lateral equilibrium or balance of the airplane.

In Figs. 5, 6 and 16 of the drawings another manner and arrangement for mounting the movable gun mount M is shown. In this adaptation of the invention, an open top cockpit forming nacelle 80, referring particularly to Figs. 5 and 6, is formed on and extending transversely across a wing 11 or other member or element of an aircraft, and the mount M of the invention is installed and movably mounted on the upper side of the nacelle across the open top of the cockpit formed therein for movement longitudinally thereof. An airplane of the biplane or multiplane type is shown in Fig. 16, in which a pair of nacelles 80 with mounts M mounted thereon, are disposed between the wings 11 at opposite sides of fuselage 10 and extending forwardly and rearwardly of the wings 11.

With an airplane equipped with the mounts M of the invention on the body or fuselage thereof and also on the wings, as shown more or less diagrammatically by Figs. 3, 4 and 16 of the drawings, it is possible to secure an effective concentration of the ordnance or guns carried by the mounts during combat with the resulting offensive and defensive efficiency of the craft armed therewith. Further, the increase in the range of fire of each gun or guns carried by a mount M due to its mobility permits of effectively arming a craft with fewer guns and gunners therefor and thus increases the load capacity of the craft. Obviously, if desired or found expedient a plurality of the mounts M can be installed and mounted for operation from and move-

ment over one cockpit or passageway and the track or supporting rails thereof.

With the airplane body or fuselage installation of a mount M on the cockpit 14 thereof, a set of controls for the airplane is preferably mounted at the normal position of the mount and seat carried thereby for operation by a gunner. In Fig. 1 of the drawings a set of controls are diagrammatically indicated by the control lever C mounted at the forward end of cockpit 14 which are operable by a gunner from the seat of the mount when the latter is in its normal forward position on the fuselage, as shown by full lines in Fig. 1.

Additional guns can be mounted for firing through openings formed in the bottom of the fuselage or body 10 of the airplane if desired to increase the defensive and offensive strength thereof and may be operated independently of the ordnance carried by the gun mount, as will be obvious to those skilled in the art.

While the invention is disclosed and intended primarily as an ordnance or gun mount, it is to be understood that the mount can be employed for various other purposes as a support or mount for other devices and instrumentalities than ordnance, and the term "gun" or "ordnance" mount as employed in the appended claims is intended to cover and include such other uses and the mounting of other devices thereon.

It is also evident that various changes, modifications, variations and substitutions might be resorted to without departing from the spirit and scope of my invention and hence I do not desire to limit my invention to the exact and specific disclosures hereof.

Desiring to protect my invention in the broadest manner legally possible, what I claim is:

1. In combination, an airplane element formed with an extended substantially horizontally disposed passageway therein, and a mount for ordnance mounted on said element for movement as a unit horizontally along said passageway.

2. In combination, an aircraft element formed with a substantially horizontally disposed passageway therein, and an ordnance mount movably mounted on said element over said passageway for movement therealong to various positions on and with respect to said element.

3. In combination, an aircraft element formed with an open top passageway therein, and an ordnance mount on said element above said passageway and movable therealong and thereover on said element.

4. In combination, an aircraft element formed with an extended open passageway therein, disposed substantially parallel to the axis thereof, an ordnance mount movable along said passageway, and a gunner's

- seat carried by and movable with said mount.
5. In combination, an aircraft element formed with an extended open passageway therein, an ordnance mount movable over and along said passageway, and a gunner's seat within said passageway carried by and movable with said mount. 70
6. In combination, an aircraft element formed with an extended passageway therein, an ordnance mount movable over and along said passageway, and a gunner's seat within said passageway and movable therealong with said mount. 75
- 15 7. In combination, an aircraft element, an ordnance mount movably mounted for movement thereover in a substantially horizontal plane to various locations thereon, and a seat carried by and movable with said mount. 80
- 20 8. In combination, an aircraft element formed with an extended passageway therein, an ordnance mount movable along said passageway, and a seat in said passageway carried by and movable with said mount, the said seat foldable to position unobstructing said passageway. 85
- 30 9. In combination, an aircraft element formed with an extended passageway therein, an ordnance mount movably mounted over said passageway and movable therealong, a gunner's seat within said passageway carried by and movable with said mount, and the said seat foldable to position unobstructing said passageway beneath said mount. 90
- 40 10. In combination, an aircraft element formed with an extended passageway therein, an ordnance mount mounted over said passageway and movable therealong, a gunner's seat within said passageway beneath said mount and foldable to position with respect to the mount unobstructing said passageway beneath the mount. 95
- 45 11. In combination, an aircraft element formed with an extended passageway therein, a mount for ordnance mounted over said passageway and movable therealong, a gunner's seat carried by and depending from said mount to position within the passageway, and guide means within the passageway for said seat. 100
- 50 12. In combination, an aircraft element formed with an extended open passageway therein, a mount for ordnance mounted for movement along said passageway, a gunner's seat supported by said mount within the passageway and movable therewith, and guide means for the seat within said passageway, the said seat foldable to position unobstructing that portion of the passageway in line with said mount. 105
- 55 13. In combination, an aircraft element formed with an open passageway therein, a mount for ordnance movable over and 110
- 60 14. In combination, an aircraft element formed with a substantially horizontally disposed passageway therein, a mount for ordnance movable along said passageway, a seat within the passageway carried by and movable with said mount, and said mount and seat movable by a gunner in position in the seat. 115
- 65 15. In combination, an aircraft formed with a substantially horizontally disposed gunner's passageway therein, a mount for ordnance movable along said passageway, a seat within the passageway carried by and movable with said mount, and means within the passageway for engagement by a gunner in the seat for moving said mount along the passageway. 120
- 70 16. In combination, an aircraft element formed with a passageway therein, a mount for ordnance movable along said passageway, a seat within the passageway carried by and movable with said mount, and members within the passageway for engagement by the feet of a gunner in the seat for forcing said mount and seat along the passageway. 125
- 75 17. In combination, an aircraft element formed with an elongated open passageway therein, a mount for ordnance mounted over and across said passageway for movement therealong, a gunner's seat within said passageway having the back thereof secured to and depending from one side of said mount, a guideway for the lower end of said seat within the passageway, a bottom for said seat pivotally mounted from the seat back and foldable to position unobstructing the passageway below said mount, and said seat movable as a unit along the passageway with said mount. 130
- 80 18. In combination, an aircraft including a control surface therefor, and a movable ordnance mount operatively connected with said control surface. 135
- 85 19. In combination, an aircraft, an ordnance mount movably mounted thereon, and means operated by movement of said gun mount for maintaining the balance of said craft by compensating for the shift in position of the mount thereon. 140
- 90 20. In combination, an aircraft, an ordnance mount movably mounted for movement to various locations thereon, and means for compensating for the change in location of said mount to maintain the balance of the craft. 145
- 95 21. In combination, an aircraft, an ordnance mount capable of movement to various locations on the craft, and means for automatically compensating for the change in 150

- location of the mount to maintain the balance of the craft.
22. In combination, an aircraft, an ordnance mount capable of movement to various locations on the craft, and means for compensating for the shift in location of the weight of said mount on the craft.
23. In combination, an aircraft, an ordnance mount capable of movement to various positions on the craft, and means operated by movement of the mount to compensate for the shift in location of the weight of the mount on the craft.
24. In combination, an aircraft including control surfaces therefor, and an ordnance mount capable of movement to various locations on the craft, the said mount connected with said control surfaces to operate the same to compensate for the change in location of the weight of the mount on the craft.
25. In combination, an aircraft including a control surface therefor, and an ordnance mount capable of movement to various locations on the craft, the control surface operated by the mount to maintain the balance of the craft with the mount moved to different positions thereon.
26. In combination, an aircraft including a body and a control surface thereof, and an ordnance mount capable of movement longitudinally along said body, the control surface operated by the mount to maintain the longitudinal balance of the body and craft.
27. In combination, an airplane including a fuselage and a horizontal stabilizer, and an ordnance mount capable of movement longitudinally of the fuselage, the horizontal stabilizer operated by movement of the mount to maintain the longitudinal balance of the craft.
28. In combination, an aircraft including a control surface, and an ordnance mount capable of movement along the fore and aft axis of the craft, the control surface operated by movement of the mount to maintain the fore and aft balance of the craft.
29. In combination, an aircraft including control surfaces therefor, and an ordnance mount capable of movement laterally of the craft, the control surfaces operated by movement of the mount to maintain the lateral balance of the craft.
30. In combination, an aircraft including a supporting surface and lateral control surfaces therefor, an ordnance mount capable of movement laterally of the craft, the lateral control surfaces operated by movement of the mount to maintain the lateral balance of the craft.
31. In combination, an aircraft including a supporting surface and lateral control surfaces therefor, an ordnance mount capable of movement on the supporting surface laterally of the craft, and the control surfaces operated by movement of the mount to maintain the lateral balance of the craft.
32. In combination, an aircraft including a supporting surface and lateral control surfaces therefor, an ordnance mount on the supporting surface movable laterally of the craft, and said mount connected with said control surfaces and operating the same during movement of the mount to maintain the lateral balance of the craft.
33. In combination, an aircraft including longitudinal and lateral control surfaces therefor, an ordnance mount capable of movement laterally of the craft, the lateral control surfaces operated by said laterally movable mount to maintain the lateral balance of the craft, an ordnance mount capable of movement longitudinally of the craft, and the longitudinal control surfaces operated by said longitudinally movable mount to maintain the longitudinal balance of the craft.
34. In combination, an aircraft element formed with an open passageway therein, an ordnance mount movable along said passageway, and means for maintaining said passageway closed in all positions of said mount therealong.
35. In combination, an aircraft element formed with an open passageway therein, an ordnance mount movable along said passageway, and means operated by said mount for maintaining said passageway closed in all positions of said mount thereon.
36. In combination, an aircraft element formed with an open passageway therein, an ordnance mount movable along said passageway, and a cover for maintaining that portion of the passageway unoccupied by said mount closed.
37. In combination, an aircraft element formed with an open passageway therein, an ordnance mount movable along and over said passageway, and a movable cover operated by said mount for maintaining the passageway closed irrespective of the position of said mount thereon.
38. In combination, an aircraft element formed with an open passageway therein, an ordnance mount movable along and over said passageway, and a cover connected to opposite sides of said mount and drawn thereby over and covering said passageway in all positions of the mount thereon.
39. In combination, an aircraft element formed with an open passageway therein, an ordnance mount movable over and along said passageway, a cover connected to opposite sides of said mount and extending over the passageway to opposite ends thereof, respectively, and means for automatically winding and unwinding said cover at opposite ends of the passageway as the said mount is moved thereover.
40. In combination, an aircraft element

- formed with an open passageway therein, an ordnance mount movable along and over said passageway, automatically winding rollers at opposite ends of the passageway, and a cover for the passageway extending thereover from opposite sides of and attached to said mount, to and attached on said rollers, respectively. 5
41. In combination, an aircraft element formed with an open passageway therein, an ordnance mount movable along and over said passageway, and a flexible cover for said passageway, said cover connected to and operated by said mount to maintain the passageway at opposite sides of the mount closed in all positions of the mount therealong. 10
42. In combination, an aircraft element formed with an open passageway therein, an ordnance mount movable along and over said passageway, an automatic winding roller at each end of said passageway, flexible strips connected to opposite sides of said mount and extending and connected to said rollers, respectively, said strips extending over and covering the passageway between the mount and the opposite ends of said passageway to form a cover therefor operated by movements of the mount to wind and unwind from said rollers. 15
43. In combination, an aircraft element formed with an open passageway therein, and a cover for said passageway formed of flexible strips extending thereover and substantially carrying out the contour of said element, the said strips mounted for movement over said passageway. 20
44. In combination, an aircraft element formed with an open passageway therein, and a cover for said passageway formed of flexible strips extending thereover and closing the same, said strips mounted at opposite ends of said passageway for movement over and across the passageway. 25
45. An aircraft element formed of a trussed frame providing an elongated interiorly unobstructed passageway therein, a series of transverse, spaced trusses across said member below said passageway, flooring for the passageway mounted on said trusses, one side of said element above said passageway formed with opposite spaced trusses providing an unobstructed opening for said passageway through the side of the member, and trusses between said side trusses and the said transverse trusses, respectively. 30
46. In combination, an airplane including a body and control surfaces, said body formed with an elongated open passageway therein, an ordnance mount movable over and along said passageway on the body, a gunner's chair in the passageway carried by and movable with said mount, and control means for operating the control 35
- surfaces mounted in said passageway and accessible and operable from said gunner's seat in normal position of the mount and seat on and in said body and passageway. 70
47. In combination, an aircraft element formed with an extended substantially horizontally disposed passageway therein and an ordnance mount embodying an annular base and annular ordnance support rotatably mounted thereon, said mount supported on said element by said base for movement longitudinally along said passageway as a unit. 75
48. In combination, an aircraft element formed with an extended substantially horizontally disposed passageway therein, and an ordnance mount of the centrally open type adapted to surround a gunner located in said passageway, said mount disposed on the element for movement longitudinally along said passageway. 80
49. In combination, an aircraft element formed with an extended open-top passageway therein, and an ordnance mount of the centrally open type mounted over and across the open-top of said passageway and adapted to surround a gunner therein, said mount movable as a unit longitudinally of said passageway to different positions on said element. 85
50. An aircraft element formed with an extended open top passageway, rail forming members along opposite sides of said passageway, and an ordnance mount supported on said rail forming members for movement along said passageway. 90
51. An aircraft element formed with an extended open top passageway therein, opposite rail forming members along and defining the open top of said passageway, said rail forming members providing structural members of the aircraft element, and an ordnance mount supported on said rail forming members for movement thereover along said passageway. 105
52. An aircraft element formed with an extended open top passageway therein, rail forming members along opposite sides of said passageway, an ordnance mount disposed above the passageway, and elements engaging said rail forming members and supporting the ordnance mount therefrom for movement along the passageway. 110
53. An aircraft element formed with an extended open top passageway therein, rail forming members along opposite sides of said passageway, an ordnance mount including a base ring mounted over and across the passageway, and rollers mounted on the base ring of said mount in engagement with said rail forming members and supporting said mount for movement over and along the passageway. 115
54. In combination, an airplane element, 120

an ordnance mount including a base and an
ordnance support adjustably carried thereon,
members on said base for movably engag-
ing the airplane element, and said base
5 mounted and supported on the element in a
substantially horizontal plane by said en-
gaging members with the ordnance mount
movable as a unit on and over a surface
of the element to different locations there-
on.

55. In combination, an airplane element,
an ordnance mount including a base, said
base movably mounted on the element, and
the said ordnance mount movable as a unit
over a surface and longitudinally of the 15
said airplane element.

Signed at Ithaca, New York, this 20th
day of December, 1924.

RANDOLPH F. HALL.
